United States Patent Office

Des. 194,097
Patented Nov. 20, 1962

194,097

TELEPHONE ENCLOSURE

James F. Antonio, 826 S. Osage St., and Floyd L. Antonio, 2250 W. Kentucky Ave., both of Denver, Colo.

Filed Nov. 29, 1961, Ser. No. 67,756

Term of patent 14 years

(Cl. D13—1)

FIG. 1

FIG. 2

FIG. 3

FIG. 1 is a front elevational view of a telephone enclosure showing our new design;

FIG. 2 is a right side elevational view thereof; and

FIG. 3 is a perspective view looking slightly upward at the front and left side thereof.

The back and top of the enclosure are plain and unadorned.

We claim:

The ornamental design for a telephone enclosure, as shown and described.
